RACING MACHINE

Armand R. Casstevens, Houston, Tex.

Application November 4, 1938, Serial No. 238,772

8 Claims. (Cl. 273—86)

This invention relates to a racing machine. An object of the invention is to provide equipment of the character described embodying a plurality of racers, preferably in the form of 5 miniature horses, mounted to move about a miniature race track with novel electrically driven apparatus for moving the racers about the track and means for automatically terminating the race with the racers stopped and maintained 10 in the order they occupy when the winner reaches the finish line.

It is another object of the invention to provide in racing equipment of the character described wherein the racers, at the beginning of 15 the race, occupy the same position as at the termination of the preceding race with mechanical means through which the racers may be moved to post position and temporarily stopped abreast and thereafter automatically released for 20 the completion of the next succeeding race.

It is another object of the invention to provide equipment of the character described wherein in the racers are caused to move at random and at variable speeds influenced solely by the 25 mechanism itself, uninfluenced by the operator.

With the above and other objects in view the invention has particular relation to certain novel features of construction, operation and arrangement of parts, an example of which is given in 30 this specification and illustrated in the accompanying drawings, wherein—

Figure 1 shows a plan view of the complete device showing the transparent covering and a portion of the race course underneath broken 35 away.

Figure 2 shows an enlarged, fragmentary, vertical, sectional view taken on the line 2—2 of Figure 1.

Figure 3 shows an enlarged, fragmentary, vertical, sectional view taken on the line 3—3 of Figure 1.

Figure 4 shows an enlarged, fragmentary, vertical, sectional view, taken on the line 4—4 of Figure 1.

Figure 5 shows an enlarged, fragmentary, plan view.

Figure 6 shows an enlarged, fragmentary, side elevation of a timing disc and associated parts.

Figure 7 shows a cross-sectional view of a 50 one way clutch employed.

Figure 8 shows a fragmentary, horizontal, sectional view, taken on the line 8—8 of Figure 3.

Figure 9 shows a wiring diagram.

Figure 10 shows a seven point switch assembly 55 shown in starting position.

Figure 11 shows a fragmentary, plan view of a switch operating mechanism.

Figure 12 shows an enlarged end view thereof, and

Figure 13 shows a fragmentary, plan view of another switch operating mechanism employed.

Referring now more particularly to the drawings wherein like numerals of reference designate similar parts in each of the figures, the numeral 1 designates a suitable cabinet or casing, 10 within which the racers and the operative mechanism therefor are enclosed, said cabinet having a transparent covering 2. Spaced beneath the covering there is a transverse horizontal partition 3 provided with the elliptical slots 4 there-around and spaced a uniform distance apart.

Beneath, and suspended from, the partition 3 there is an elliptical frame designated generally by the numeral 5 having an elevated central portion 5a and which declines in steps, from said 20 central portion as shown more clearly in Figures 2, 3 and 4. This frame 5, 5a is also suitably supported from the bottom of the cabinet by suitable upstanding posts 6.

The racers, in the present instance being miniature horses, are designated by the numerals 7. They are supported on the upper ends of the supporting rods 8 which move in the slots 4. The lower ends of these rods are fastened to endless chains, as 9, which move around underneath the 30 race course and which are concealed from view. These chains travel about the rollers 10 which are mounted on ball bearings on the vertical rods 11. These rods are supported on the outwardly turned, lower margin, or skirt, of the frame 5, 5a 35 and in turn support the sections of the partition 3, between the respective slots 4, forming the race track proper. The rods 8 which support the racers 7 carry suitable guides 12 which move in the guideways, or tracks, 13, 13 carried 40 on the rods 11, as shown in Figure 2.

The chains 9 are separately driven from independent motors 14. The driving mechanism is illustrated more clearly in Figures 2 and 5. A 45 description of the driving connection between one motor and the sprocket chain driven thereby will be applicable to all.

The numeral 15 designates a vertical shaft mounted to rotate in suitable bearings in the bracket 16. This bracket is mounted on the motor supporting platform 17. The driving shaft 18 of the motor has a worm gear 19 thereon which is in mesh with the helical gear 20 fixed on the vertical shaft 15 whereby said last 50 55

mentioned shaft is driven by the motor, all as illustrated in Figures 2 and 5.

Fixed on the upper end of the shaft 15 there is a sprocket wheel 21 which drives the sprocket chain 22, operating thereover and this chain in turn drives the sprocket wheel 23 fixed on the lower end of the short shaft 24 which operates in a suitable bearing in the frame 5, 5a. Fixed on the upper end of the shaft 24 is a sprocket wheel 25 which is in mesh with, and drives the corresponding sprocket chain 9 causing the same to revolve and move the corresponding racer 7 about the track.

The shaft 15 also has a helical gear 26 fixed thereon which is in mesh with and drives a reversible worm gear 27 fixed on the horizontal governor shaft 28. On this last mentioned shaft there is a conventional governor arrangement 29 embodying a brake disc 30. The governor mechanism, including said disc, rotates with the shaft 28 and the disc 30 is slidably longitudinally relative to the shaft whereon it is mounted.

Fixed on the shaft 15 there is also a pulley 31 over which the belt 32 operates. This belt also 26 operates around an idler pulley 33 and also about a pulley 34 which rotates in a vertical plane, as shown in Figure 1. The pulley 34 is fixed on a shaft 35 which in turn is mounted in a suitable bearing in the standard 36 upstanding from the bottom of the cabinet 1. Loosely mounted on each shaft 35 there is a disc 37 attached to which there is a ratchet wheel 38. Adjacent this ratchet wheel there is a push bar 39 whose outer end is accessible to an operator. This push bar has brackets, as 40, attached thereto and pivotally mounted on each bracket and cooperating with each ratchet 38 there is a dog 41 which is maintained in cooperating relation with the corresponding ratchet by the pull spring 42, one end of which is attached to the bar 39 and the other end of which is attached to said dog 41. The disc 37 may turn freely on the shaft 35 in the direction indicated by the arrow in Figure 6. Each disc 37, however, is connected to its shaft 35 by conventional one way clutch 43 of such construction that when the corresponding motor is started and the shaft 35 correspondingly driven, said shaft will be clutched with and will drive the disc 37, as shown in Figure 7.

The discs 37 are identical so that each racer will have an equal chance with the others. Each disc 37 has projections as 44 on one face thereof, the projections of each disc being arranged at random as to length and spacing but being arranged in a circular row as more clearly shown in Figure 6 as the discs 37 are identical, the motor speeds equal, and the differences of the lengths of track are compensated by varying the diameter of the gears 22 as shown in Figure 1, each racer has an equal chance to win.

Pivotedly mounted on the upper end of an upstanding standard 45 there is a cross-lever 46 whose ends are overturned forming the arms 47, 48. The arm 47 is adjustable as to length by a turn buckle 49 and said arm terminates in an enlarged contact surface 50 in the path of the projections 44. The free end of the arm 48 terminates in a brake shoe 51 normally held in contact with the brake disc 30 by the pull of the coil spring 52, one end of which is attached to the upper end of the standard 45 and the other end of which is attached to the lever 46. As the contact surface 50 is successively contacted by the projections 44, as the disc 37 turns, the brake shoe 51 will be successively released from the

brake disc 30 and as the contact surface 50 is successively released by the projections 44, the brake shoe 51 will be pressed against the disc 30 in accordance with the pull of the spring 52. The shaft 28, therefore, will rotate at variable rates of speed causing the speed of movement of the corresponding racer 7 to vary as it moves about the race course.

Referring to Figure 1, A will be hereinafter referred to as post position and B will be herein-after referred to as finish position. At the said last mentioned position are the vertical shafts 53 having upper end bearings in the partition 3 and the lower end bearings in the frame 5. These shafts having the rollers or drums 54 rotatably mounted thereon around which the chains 9 move. They have the four blade turnstiles 55 fixed on their upper ends and the two blade turnstiles 56 fixed on their lower ends.

At post position are the vertical shafts 57 having upper end bearings in the partition 3 and lower end bearings in the frame 5 with four blade turnstiles 58 fixed on their upper ends and two blade turnstiles 59 and four blade turnstiles 59a fixed on their lower ends. The shafts 53, 57 also have guideways or tracks 13 thereon in which the guides 12 move as the racers proceed around the track.

Incorporated into the electrical circuit 60, leading to each motor, there is a magneto switch 61 designated generally by the numeral 61 associated with which there is a brake arm 62 whose free end is overturned toward the disc 30 and carries a brake shoe 63. When the circuit, leading to the motor, is broken the magneto switch will be effective to set the brake shoe 63 against the disc 30 to at once stop the rotation of said disc. The motor shaft 64 is connected to the driving shaft 18 of the motor by means of a suitable differential clutch 65 whose members have a yieldable connection forming means for absorbing the shock incidental to the sudden stoppage of rotation of the disc 30 thus protecting the mechanism driven by the motor from undue stress or breakage.

The numerals 66 designate switch boxes for electrical switches 61. These switches are located adjacent the turnstiles 59 to be operated thereby. The numerals 68 designate switch boxes wherein are located the switches 69, said boxes 68 being located adjacent the turnstiles 56 so that the switches may be operated thereby. There is a seven pole, double throw switch mechanism embodying the shift plate 70 having the pairs 71, 71a of contact tongues thereon and insulated therefrom. The tongues 71 are electrically connected with the wiring 72 and the tongues 71a are connected into the wiring 73 into which the switches 69 are also connected. The switches 61 are incorporated into the wiring 72 leading to the tongues 71. One main lead in wiring 74 separates into the branches 72, 73. Associated with the shift plate 70 are the contact tongues 75 from which the wiring 76 leads to the respective magneto switches 61. The plate 70 may be shifted into one position to electrically connect the tongues 71, 75 to complete circuits 72 through wiring 76 to the motors and to another position to electrically connect the tongues 71a, 75 to complete the circuit 73 on through the wiring 76 to the motors.

Connected to one end of the shift plate 70 are the coil pull springs 77 which normally hold the plate 70 in position to maintain the contact tongues 71a, 75 electrically connected. At its

- other end the switch plate 70 is formed with a catch 78 and there is a suitable latch mechanism 79 designed to engage said catch and hold the plate 70 in its other position, when shifted thereto, with the contact tongues 75, 71 electrically connected. The shift plate 70 may be manually actuated by a push arm 39a connected to a cross bar 39b connecting the push bars 39 and movable therewith.
- 10 At the starting of any particular race the racer which won the preceding race will be at position B, having opened one of the switches 69 by coming into contact with the corresponding turnstile 55 and actuating its shaft 53 to thereby 15 actuate the corresponding turnstile 56 and open said switch thus breaking the circuit to all motors and stopping all of the racers and the other racers will be located on the race course in their respective positions behind the finish position B.
- 20 Upon actuation of the plunger bars 39, in the present illustration, toward the right the switch plate 70 will be correspondingly actuated to carry the tongues 71 into electrical contact with the tongues 75 as shown in Figures 9 and 10 and 25 the plate 70 will be latched in that position by engagement of the latch 79 with the catch 78. The push bars 39 also carry a cross bar 39c. Opposite this there is a shiftable yoke 39d, said cross bar and yoke having inwardly extending 30 arms 39e opposite the respective switches 67. One of the push bars 39 is operatively connected with the yoke 39d through a pivotally mounted shift lever 39f having a sliding pivotal connection at one end with the push bar 39 and at its 35 other end with the yoke 39d. Upon actuation of the push bars 39 toward the right as above stated, the arms 39e will be correspondingly actuated to close all of the switches 67. Upon release of the plunger bars they will be returned 40 to their original position by the pull spring 83. Upon return of the plunger bars the dogs 41 will engage the corresponding ratchet wheels 38 thus 45 spinning the discs 37. Since these discs rotate independently they will turn different distances due to variations in friction with their respective 50 shafts 35 and due to slight variations in their momentum to the end that the corresponding projections 44 of the respective discs will assume varying angular relations with respect to their corresponding shafts. Therefore the influence 55 of each disc 37 (while being driven by its motor), on said motor will vary with respect to the influence of other of the discs 37 on their corresponding motors; that is, the discs 37 will not 60 operate to slow up, or permit acceleration of, their respective motors at the same time so that during the progress of the race the racers will not move at uniform speeds but a racer will move faster when a projection 44 of its corresponding disc has operated to release the corresponding 65 brake shoe 58 from its disc 39 and will be slowed up when the corresponding friction surface 51 has been released by a projection 44 to permit the brake shoe 51 to brake the disc 39.
- 65 Preliminary, therefore, to the actual beginning of the race the racers 7 will move around the track to post position A of Figure 1. The first racer reaching said position will strike a blade of the turnstile 58 partially turning the shaft 57 70 and operating through the corresponding turnstile 59 to open a switch 67 thus stopping the corresponding motor with the racer at post position and as the subsequent racers come into post position the corresponding switches 67 will be successively broken thus stopping all of the 75
- motors with the racers abreast at post position as shown in Figure 1. As the racers break their corresponding switches 67 the four blade turnstiles 59a will operate to close the switches 81 in a circuit 82 leading from the other lead in wire 5 74a to a retarded relay 83. This relay has a delayed action and operates a few seconds after switches 81 are closed and thereupon acts to energize the solenoid 83a which releases the latch mechanism 79 from the catch 78 permitting the 10 springs 77 to return the switch bar 70 to original position bringing the contact tongues 71a into electrical connection with the corresponding tongues 75 and at the same time energizing the solenoids 83b and actuating the yokes 84, 84 connected to the switches 69 to close said switches thereby completing circuits to all of the motors. The solenoids 83a, 83b are connected by wiring 74b, 82a with wiring 74, 82. The racers are thereupon moved around the race track. As they pass 15 the finish position B they will partially rotate the shafts 53, the two blade turnstiles 56 correspondingly turning idly. The racers will move on around the track at variable rates of speed from time to time due to the action of the discs 37 on the corresponding motors. As the racers pass 20 post position A, in approaching the end of the race, they operate the turnstiles 59a to open the switches 81 thus cutting the retarded relay 83 out of the circuit. This releases the solenoids 30 83b and the springs 85 will thereupon operate through the yokes 84 to release the switches 69 so that the winning racer, upon reaching finish position, may turn the shaft 53 which will operate the turnstile 56 to open the corresponding 35 switch 69. As the racers pass post position in approaching the end of the race, the two blade turnstiles 59 will perform a partial idle rotation at this time not affecting the switches 67 which will remain open. The racers move on to finish 40 position B, the winner further turning the corresponding turnstile 55, which in turn will further rotate its shaft 53 and impart a further rotation to the turnstile 56 on the lower end of said shaft. This, in turn, will now operate to open a switch 45 69 of the circuit 13, stopping all of the motors and racers connected therewith. The new race will be started as hereinbefore described.
- In order to further explain the operation of the game, a resume of the switching and circuits will 50 be given.
- At the end of a race, switch 69 has been opened, thereby stopping all horses. To begin a new race, push bars 39 are actuated, moving the switch plate 70 (Fig. 10) which connects the contacts 55 75 and 71. This movement also closes all switches 67, at the post position, which were open. In this manner, the starting circuits are made between the motors and the lead in wires. These circuits comprise line 74, switches 67, at the post 60 position, branch 72, contacts 71 and 75, wiring 76, magnetic brakes 61 (which release when current is passed through them) electrical circuit 60, motors, and back to the inlet line 74a. Each motor has its individual switch 67 which is opened 65 when the corresponding horse reaches post position, thereby stopping each horse individually and in line with each other at the post position.
- It may be noted that there is a wiring 73 and circuit 82 across the inlet lines 74, 74a and a set 70 of switches 81, 81 at post position which are connected in series. These switches control a retarder relay 83 which operates a short interval of time after current has started flowing through it. This relay controls current to 75

electro-magnet 83a which pulls the latch 79 holding the switch plate 70 so that contacts 71 and 75 are engaged, and the electro-magnet 83b which actuates the yokes 84 (Fig. 11) to close the switch 69 which was opened by the winning horse of the preceding race.

The switches 81 are located at the post position, and as the horses line up at the post, these switches are closed. The horses are stopped at post position as they open switches 67 located at the post position. As the last horse comes to the post, it stops momentarily until relay 83 acts, then all of the horses move forward by circuits hereinafter described. At the time that the last horse closes the last switch 81, relay 83 then acts to energize magnet 83a (Fig. 10), and release the switch plate 70 allowing the springs to move said plate so that contacts 75 and 71a are engaged. The horses then move around the track while connected in this running circuit containing inlet line 14, switches 69, branch 73, contacts 75 and 71a, wiring 76, brake 61 and electrical circuits 60 and motor, thence to line 74a. As the horses leave the post position A and pass the finish position B, the switches 69 do not open, as the turnstile is two-bladed as hereinbefore disclosed. Then as the horses pass the post position, switches 81 are opened releasing the relay 83 which allows the electromagnets 83a and 83b to become inactive.

As the first horse reaches the finish position, it opens switch 69 and all the horses are stopped in their relative positions as determined by the governor control as hereinbefore described. The horses are then in position for the push bars 39 to be again actuated to start the horses on another race.

What I claim is:

1. A racing machine comprising a race track having a post, or starting position, and a finish position, means for moving the racers about the track from finish position to post position, means for automatically rendering the moving means temporarily inoperative when all the racers reach post position and then rendering the moving means operative, means for thereafter maintaining the moving means operative to move the racers completely around the track to post position and on to finish position and means at finish position arranged to be actuated, upon arrival of the leading racer at final finish position, and effective to render the moving means inoperative and to stop all the racers.

2. A racing machine comprising a race track, a plurality of racers movable about the track, means for moving the racers, said moving means including an electric motor for each racer, a series of starting circuits leading to the motors, manually operable means for completing these circuits, switches in the circuits, means operative by the moving means to open the switches to break the circuits, another series of running circuits leading to the motors having switches therein each common to all the circuits of said other series, electrically controlled means arranged to be rendered effective upon the breaking of said series of starting circuits, to control said manually operable means whereby said running circuits to the motors will be completed and whereby said switches controlling said running circuits will be closed and means operative by the moving means arranged to open said common switches.

3. A racing machine comprising a race track having post and finish positions, a plurality of racers movable about the track, means for mov-

ing the racers, said moving means including an electric motor for each racer, a starting and a running circuit associated with the motors, switching means formed to connect the motors into either of said circuits, said switching means being manually movable to connect the motors to the starting circuit, and automatically movable to connect the motors to the running circuit, electrical control means arranged to be actuated by said racers at the post position and effective to stop the individual motors, thereby stopping each racer at post position, said running circuit having means arranged to be actuated by the first racer that passes the finish position to break the circuits to the motors, and to stop the racers at finish position, said control means being formed to move said switching means from the starting position and to automatically reset said means to stop the racers at the finish position.

4. A racing machine comprising a race track having post and finish positions, a racer movable about the track, means for moving the racer, said moving means including an electrical motor, a starting circuit and a running circuit for the motor, switch means movable manually to one position to connect the motor into the starting circuit, latch means for latching the switch means in said position, means for automatically moving the switch means to connect the motor into the running circuit, means arranged to be actuated by the racer at post position to break the starting circuit, electrical control means for releasing the latch means, means arranged to be actuated by the racer at post position for completing the circuit to said electrical control means and means positioned to be actuated by the racer at finish position and effective to break the running circuit.

5. A racing machine comprising a race track having post and finish positions, a plurality of racers movable about the track, means for moving the racers, said moving means including an electric motor for each racer, a starting circuit connecting all the motors in parallel with a supply line and a running circuit connecting all the motors in series, switching means formed to connect the motors into either of said circuits, said switching means being manually movable to connect the motors to the starting circuit, latch means for latching the switch means in said position, an electro-magnet adapted to move said latch means to release the switching means, electrical switches in the starting circuit arranged to be actuated by said racers at the post position and effective to stop the individual motors, thereby stopping each racer at post position, switches located at the post position connected to control means adapted to control said electromagnet, said running circuit having switches in series arranged to be actuated by the first racer that passes the finish position to break the circuits to the motors to stop the racers at finish position, said control means being formed to move said switching means from the starting position and to automatically reset said means to stop the racers at the finish position.

6. An intermittent drive for a racing device comprising a motor, a power take-off shaft driven by the motor, a brake disc operatively connected to said shaft, a brake shoe adapted to contact said brake disc, a rotatable disc having an uneven surface, means operatively connecting the brake shoe and the surface of the rotatable disc whereby the brake disc is intermittently contacted by the brake shoe, said intermittent con-

tact being caused by the roughness of the surface of the disc.

7. A racing machine comprising a race track having a post, or starting position, and a finish position, a plurality of racers movable about the track, means for moving the racers about the track including an electric motor, a starting circuit leading to the motor effective to energize the motor to drive the racer to post position, a switch in the circuit for stopping the racer at post position, a running circuit connected to the motor effective to energize the motor to drive the racer from post position completely around the track to post position and on to finish position, a switch in the running circuit effective to break the circuit when the racer reaches the finish position after having gone completely around the track to stop the racer, switch means common to

both circuits to switch the motor from one circuit to the other circuit.

8. In a racing machine including a track and racer movable about the track, means for moving the racer about the track, and a motor for driving said moving means; means for controlling said moving means to vary the speed of each racer comprising a shaft, a disc rotatably mounted on the shaft and having an uneven surface, means for clutching the disc to the shaft, means for rotating the disc independently of the shaft, means for rotating the shaft, a member having a contact face bearing against said uneven surface whereby the member is moved as the disc is rotated, means operatively connecting the member and said moving means whereby the speed of the racer is varied in accordance with movement of the member.

ARMAND R. CASSSTEVENS.
